UNITED STATES PATENT OFFICE.

CYRUS L. SULZBERGER, OF NEW YORK, N. Y.

DESIGN FOR SKIRT-BINDING.

SPECIFICATION forming part of Design No. 29,780, dated December 6, 1898.

Application filed November 10, 1898. Serial No. 696,089. Term of patent 14 years.

To all whom it may concern:

Be it known that I, CYRUS L. SULZBERGER, of the city of New York, borough of Manhattan, in the county and State of New York, have 5 invented and produced a new and original Design for Skirt-Binding, of which the following is a full, clear, and exact description.

Reference is to be had to the accompanying drawings, forming a part of this specification, o in which similar characters of reference indicate corresponding parts in all the views.

Figure 1 is a face view of a skirt-binding showing my design. Fig. 2 is a rear face view of the same, and Fig. 3 is an edge view of the 5 same.

The design consists of a body A, a depending brush B, and stitching C, overlying part of the head B' of the brush B and the lower

end of the body A, the upper portion of the head abutting against the lower end of the 20 body, with the stitching covering the extreme upper end of the head of the brush both at the front and rear faces of the binding.

The leading features of the design consist of a body A, a depending brush the head of 25 which abuts against the lower edge of the body, and stitching overlying part of the brush-head and the lower end of the body.

I claim—

The design for skirt-binding, as herein 30 shown and described.

CYRUS L. SULZBERGER.
